UNITED STATES PATENT OFFICE.

EDWIN B. CANTRELL AND GEORGE E. MILLER, OF SAN FRANCISCO, CALIFORNIA.

CAP-PULLER.

1,291,638.

Specification of Letters Patent. Patented Jan. 14, 1919.

Application filed December 13, 1916; Serial No. 136,817. Renewed July 19, 1918. Serial No. 245,774.

To all whom it may concern:

Be it known that we, EDWIN B. CANTRELL and GEORGE E. MILLER, citizens of the United States, residing at the city and county of San Francisco and State of California, have invented new and useful Improvements in Cap-Pullers, of which the following is a specification.

In garages and shops, particularly where repair work is done on "Ford" cars, it frequently happens that the bearing bushings or the roller bearings in the rear shaft housing have to be removed, either because they are worn or for other reasons, or that the 10 felt washer at the end of the axle housing has to be removed. The removal of any one of the parts mentioned requires considerable time as the end caps on the axle housing must first be taken off. These caps are 15 driven or pressed into position and their removal is, therefore, more or less difficult, as it requires both time and skill to accomplish this operation without damaging the caps.

One of the objects of the present invention 20 is to provide a simple, substantial cap puller, whereby any individual, whether skilled or otherwise, can remove the caps without any unnecessary loss of time or any danger of damaging the caps. Further objects will hereinafter appear.

The invention consists of the parts and the construction and combination of parts as hereinafter more fully described and claimed, having reference to the accompanying drawings, in which—

Figure 1 is a section of one end of a rear axle housing, showing the application of the invention.

Fig. 2 is a plan view of the cap puller.

Referring to the drawings in detail, A indicates one end of an axle housing; 2 the axle; 3 the axle spindle; 4 the roller bearings; 5 the bearing bushing; and 6 the end cap, between which and the end of the axle 45 housing is mounted a felt washer 7. This cap is either pressed or driven on the end of the axle housing and its removal presents more or less of a difficult problem, as previously stated. A cap puller has been provided in the present instance whereby it may be quickly removed without damaging the cap.

This cap puller is constructed as follows: 50 8 indicates a cone-shaped housing, one end of which is open, as at 9, to permit it to be

slipped over the axle spindle 3 and the cap 6. Extending through the closed end 10 of the casing is a screw 11, the inner end of which is pointed, as at 12, to engage the center of the spindle 3. This screw may be provided 60 with a square head on its outer end to permit it to be turned by a wrench, or, as here shown, by a crank-shaped handle extension 13.

Formed on top of the casing, near the 65 open end, is a lug 14 through which passes a screw 15, and formed just beneath said lug is a slot 16 through which extends a comparatively heavy spring 17. One end of this spring is suitably secured in a lug 18, 70 formed on top of the casing, while the opposite end is hook-shaped and extends through the slot 16. The spring tension is such that it will normally engage the upper wall 18' of the slot or the point of the screw 15, thus 75 normally retaining the hook-shaped end 19 of the spring withdrawn with relation to the interior open end of the casing.

The operation of the cap puller will be as follows: The screw 15 is first turned to a 80 point where it permits the hook-shaped end 19 of the spring 17 to assume the dotted line position shown in Fig. 1. The housing is then slipped over the spindle 3 and the cap 6 to assume the position shown in Fig. 1. 85 The screw 15 is then turned to force the point against the spring, or, in other words, to drive the hook 19 behind the edge of the cap where it will securely engage the same. The screw 11 may then be turned, either by 90 means of the handle 13 or by a wrench, until sufficient pressure is brought to bear against the end of the axle spindle to pull the casing in the direction of arrow a.

A continued turning of the screw 11 will 95 then remove the cap, as the casing will continue traveling in the direction of arrow a as long as turning movement is imparted to the screw. The removal of the cap is in this manner easily accomplished without loss of 100 time and without any danger of damaging the cap. The removal of the cap 6 not only permits the insertion of a new washer 7, but also permits the removal of the roller bearings 4 or the bearing bushing 5, and as the 105 cap may be driven back into place comparatively little time is required.

The interior diameter of the open end of the casing is just sufficient to permit it to fit the cap 6 and as the whole construction 110

and operation of the cap puller is simple, it is obvious that any individual, whether skilled or not, may perform the operation.

The materials and finish of the several parts of the cap puller are such as the experience and judgment of the manufacturer may dictate.

We wish it understood that various changes in form, proportions and minor details of construction may be resorted to within the scope of the appended claims, and that we do not wish to limit ourselves to the specific design and construction here shown, except as required by the scope of said claims.

Having thus described our invention, what we claim and desire to secure by Letters Patent is—

1. A cap puller comprising a cone-shaped holder open at one end and closed by a head at the opposite end, a screw rod centrally positioned in the head, a spring secured to the holder, and a hook-shaped catch formed on

one end of the spring adapted to be moved into or out of alignment with the open end of the holder.

2. A cap puller comprising a cone-shaped holder open at one end and closed by a head at the opposite end, a screw rod centrally positioned in the head, a spring secured to the holder, a hook-shaped catch formed on one end of said spring to engage the cap, and a screw mounted in the holder engageable with the spring to engage the catch with the holder, and turnable to allow the spring to retract and withdraw the catch and release the cap.

In testimony whereof we have hereunto set our hands in the presence of two subscribing witnesses.

EDWIN B. CANTRELL.
GEORGE E. MILLER.
